(57) **CLAIM**

I claim the ornamental design for a string support for a guitar, as shown and described.

DESCRIPTION

FIG. 1 is a perspective front view of a string support for a guitar showing my new design;

FIG. 2 is a front view thereof, the back view being a mirror image;

FIG. 3 is a left side view thereof, the right side view being a mirror image;

FIG. 4 is a top view thereof;

FIG. 5 is a bottom view thereof; and,

FIG. 6 is a perspective view of the string support shown in use. The broken lines showing a guitar neck and body in FIG. 6 depict environmental matter and form no part of the claimed design.
